MES PATERSON, OF ELIZABETH, ASSIGNOR TO RICHARD H. REEVE AND BENJAMIN C. REEVE, OF CAMDEN, NEW JERSEY.

Design No. 4,674, dated February 21, 1871.

DESIGN FOR AN OIL-CLOTH PATTERN.

The Schedule referred to in these Letters Patent and making part of the same.

, JAMES PATERSON, of Elizabeth, county of Union, te of New Jersey, have invented or produced a sign for an Oil-cloth Pattern, of which the follow- is a specification.

The figure in the accompanying drawing which as a part of this specification illustrates my design, main feature of which consists of a series of ob- g-bordered tablets, A A A, arranged in respect to other in the peculiar manner shown, each tablet taining a panel, B, within which may be printed a al and foliated ornament.

The oblong spaces E between the tablets are orna- ited as shown.

Irrespective of the colors employed,
I claim—

The design for an oil-cloth pattern substantially as described, and as illustrated in and by the accompany- ing drawing.

In testimony whereof I have signed my name to this specification in the presence of two subscribing witnesses.

JAS. PATERSON.
